UNITED STATES PATENT OFFICE.

ARTHUR E. HAUCK, OF BROOKLYN, NEW YORK.

OIL-BURNING APPARATUS.

1,090,395.

Specification of Letters Patent. Patented Mar. 17, 1914.

Application filed May 31, 1911. Serial No. 630,525.

To all whom it may concern:

Be it known that I, ARTHUR E. HAUCK, a citizen of the United States, residing at Brooklyn, in the county of Kings and State of New York, have invented certain new and useful Improvements in Oil-Burning Apparatus, of which the following is a full, clear, and exact specification.

This invention relates to oil burning apparatus, and has especial reference to the burning of liquid fuels, such as kerosene, crude oil, etc., for heating purposes, such as in metallurgical and metal working operations, such as brazing, tire fitting, shrinking, etc.

I have herein shown and described a portable apparatus particularly constructed and adapted for use in applying and removing the tires of locomotive and other wheels, but also adapted for various other uses.

As generally constructed, the apparatus embodies a truck carrying a liquid fuel reservoir, connected with a preliminary vaporizer and partial burner, an extinguishing tube and a final burner, which latter is shown herein in the form of a flexible adjustable ring adapted to embrace the tire or other device to be heated by the heat produced by the final burning of the fuel.

I provide, where a greater degree of heat is required, an auxiliary fuel supply connected to the final burner, but passing through the primary combustion chamber so that the heat therein can be utilized not only for vaporizing the fuel for the partial combustion but the auxiliary fuel for the final burner as well.

The invention also consists in the various combinations of parts and details of construction as will be more fully understood in connection with the description of the accompanying drawings, wherein—

Figure 1 is a side elevation of an apparatus embodying the invention; Fig. 2 an end elevation; Fig. 3 a detail view of a slightly modified partial combustion chamber; Fig. 4 a detailed view of the auxiliary fuel nozzle; Fig. 5 a cross-section of the flexible burner, as adapted for heating tires, etc.; and Fig. 6 is an end view of the partial burner.

1 represents a truck or platform having an upright standard 2, which carries an upper adjustable section 3, herein shown as adjustable by means of a pin 4 passing through poles 5 in the standard 2.

6 represents a liquid fuel tank which is provided with a pump 7 for producing a pressure on the surface of the fuel, and a gage 8.

9 is a fuel outlet pipe provided with a valve 10 and connected by pipe 11 to a partial burner 13, which partial burner 13 is connected with an extinguishing pipe 14, and the latter to the final burner 15. The pipe 11 is connected to a strainer 16, then to a valve 17 which controls the flow of oil both to the main supply pipe 18 and the auxiliary supply pipe 19, each of these pipes 18 and 19 being provided with check valves 20 closing toward the tank, to prevent any back pressure from forcing liquid in pipes 18 or 19 back into the tank. The pipe 18 is formed into a coil 21 which coil 21 is connected to a hollow casting 22 containing an oil passage 23, and thence a pipe 24 leads backward to a forwardly projecting nozzle 25. This nozzle consists of a plug having a small hole through which the fuel will issue in the form of gas or vapor, which will be ignited and burned in part within the perforated cylinder 26, which, as shown, is carried by casting 22 and incloses the coil 21. The casting 22 is attached to a head 27 by arms 28, which head 27 is carried by the extinguishing pipe or chamber 14.

29 represents an oil pan adapted to contain a small quantity of oil which when ignited will heat the pipe 18, coil 21, casting 22 and vaporizes the oil therein so that it will issue from the nozzle 25 in the form of gas and ignite itself, it being understood that the air pressure in the tank thus forces the flow of oil, valves 10 and 17 being open. The air supply is such that the blast of vaporized fuel issuing at a high velocity from the nozzle 25 in line with the extinguishing chamber 14 will not burn completely, but will be extinguished upon passing into pipe 14 through the head 27. There will thus be contained in the chamber 14 a large volume of combustible gas, of which only a small proportion of the original fuel supply has been burned, and this gas will be forced by the blast through pipe 14 to the final burner 15.

As herein shown, the final burner 15 comprises a flexible pipe made of metal hose or jointed sections, provided with holes around its inner periphery and plugged ends 30 which may be clamped together as by a chain 31 to embrace the tire of a wheel 32.

The burner 15 carries a series of supports 33 which contact with the wheel to be heated, and thereby form a combustion space between the periphery of the wheel and the final burner 15.

34 is a shield of asbestos fastened to the inner periphery of the burner 15 for protecting the burner tube from excessive heat, and also deflecting the heat inwardly toward the tire which is to be heated. Preferably, the asbestos 34 will have a metal face 35, suitable holes being provided as 37 where the gas is to issue. The final burner tube 15 is connected preferably at an intermediate portion to the extinguishing tube 14.

In some instances, it is desirable to secure additional heat at the final burner over and above that supplied by the means just described, and this is accomplished by the auxiliary pipe 19 controlled by valve 38, and having a coil 39 within the head 27, and then leading the heated additional fuel mixture by pipe 40 to oppositely extending nozzles 41 (see Fig. 4). As shown in the detail of Fig. 4, these nozzles 41 consist of plugs having small passages or nozzles 42 similar to the nozzles 25, and an enlarged dirt or sediment chamber 43 for trapping any solid particles which may pass through the pipe 40. It will be seen that the auxiliary fuel supply will be vaporized in coil 39 and pipe 40 by the heat from the primary partially consumed gases, and then upon issuing from the nozzles 42 mix with the other gases. In practice I have found that the gases from the nozzle 25 which are extinguished in the extinguishing chamber 14 because of deficiency of air, will sometimes re-ignite upon issuing from the holes 37 of the final burner 15, by reason of their heat, but in case this reignition should not occur they can be readily ignited. It will be understood that the flow of oil will be readily controlled by valves 17 and 38 to secure any desired degree of heat at the final burner 15.

In Fig. 3, a slight modification is shown, in which the heating coil 21 is dispensed with, and the oil is vaporized at a nozzle 45 by a blast of compressed air from a source 46, the nozzle 45 being inclosed within a perforated cylinder 47, the fuel mixture being extinguished upon passing into head 27 and extinguishing chamber 14 as heretofore described, the other parts remaining substantially the same.

For adjusting the height of the apparatus, a lever 48 (Fig. 2) connected to the upper section of standard 3 and mounted on a fulcrum 49 may be employed.

It is thought that the construction and operation of the invention will be fully understood from the foregoing description.

So far as I am aware, it has not heretofore been proposed to vaporize liquid fuel by its own heat of combustion and to then

extinguish the flame and burn the residue at a final burner, nor, so far as I am aware, has it been proposed to utilize the heat of the extinguished gases for vaporizing an auxiliary supply of fuel and simultaneously 70 burning the resultant mixture at the final burners, for obtaining a high degree of heat.

It will be understood that the parts herein shown as especially adapted for heating tires are not the only form in which the invention 75 may be applied, as the construction of the final burner will be adapted for the purposes in view, and various modifications and changes within the scope of the appended claims may be made without departure from 80 the invention.

Having thus described my invention, I declare that what I claim as new and desire to secure by Letters Patent is—

1. The combination in an oil burning apparatus, with means for supplying vaporized oil, a burner for partially consuming a portion of the vaporized oil and a partial combustion chamber for said burner, of an extinguishing passage leading from said combustion chamber, and a final burner at the end of said extinguishing passage and connected to said oil supplying means. 85

2. The combination of a partially consuming burner having a nozzle, an oil supply pipe leading to said nozzle, a flame-extinguishing chamber communicating with said burner, a final burner in operative relation to said flame-extinguishing chamber, and a second oil supply pipe leading to said 90 final burner. 95

3. The combination of a partially consuming burner having a nozzle, a source of vaporized oil, a supply pipe leading from said source to said nozzle, a flame-extinguishing chamber communicating with said burner, a final burner communicating with said flame-extinguishing chamber, and a second fuel supply pipe leading to said 100 final burner. 110

4. The combination with means for forcing and vaporizing oil, of means for partially burning a portion of the forced vaporized oil, means for extinguishing the partially burned vaporized oil, a final burner 115 for completing the combustion, and means for feeding an additional supply of oil directly to said final burner.

5. The combination of a partially consuming burner having a nozzle, an oil supply 120 pipe leading to said nozzle, a portion of said oil supply pipe being in heating relation to said burner, a flame-extinguishing chamber communicating with said burner, a final burner communicating with said flame-extinguishing chamber, and a second oil supply pipe leading to said final burner. 125

6. The combination with means for feeding oil under pressure, heating and vaporizing it, of a partial combustion chamber 130

having a burner, a chamber for receiving the burning vapor and extinguishing it, and a final burner for completing the combustion and separate connections between said feeding means and each of said burners.

7. The combination of a partially consuming burner having a nozzle, an oil supply pipe leading to said nozzle, a portion of said oil supply pipe being in heating relation to said burner, a flame-extinguishing chamber for said burner, a final burner communicating with said flame-extinguishing chamber, and a second oil supply pipe leading to said final burner, a portion of said second supply pipe being in heating relation to said partially consuming burner.

8. The combination of a partially consuming burner having a nozzle, a source of vaporized oil, an oil supply pipe leading from said source to said nozzle, a flame-extinguishing chamber communicating with and in alinement with said burner, a final burner in operative relation to said flame-extinguishing chamber, and a second oil supply pipe leading through said flame-extinguishing chamber to said final burner.

9. The combination in a portable, self contained oil burning apparatus of a base carrying means for feeding and vaporizing oil, a partial combustion chamber having a burner for burning a portion of the vapor to heat the liquid supply, connections between said burner and said oil feeding means, an extinguishing chamber for extinguishing the flame when the oil discharged through said burner is partially consumed, a final burner having connection with said extinguishing chamber, and means for maintaining a forced flow of gas through said chambers to said final burner.

10. The combination with means for feeding and vaporizing oil, of a partial combustion chamber having a burner for burning a portion of the vapor to heat the liquid supply, an extinguishing chamber for extinguishing the flame when the oil discharged through said burner is partially consumed, a final burner having connection with said extinguishing chamber, separate pipe connections for said first-named burner and said final burner with said oil feeding means, and means for maintaining a forced flow of gas through said chambers to said final burner.

11. The combination of a partially consuming burner having a nozzle, an oil supply pipe leading to said nozzle, a portion of said pipe being in heating relation to said nozzle, a flame-extinguishing chamber for

said burner, a final burner in operative relation to said flame-extinguishing chamber, and a second oil supply pipe leading through said flame-extinguishing chamber to said final burner, a portion of said second oil supply pipe being disposed in heating relation to the flame of said burner.

12. The combination with an oil supply source, of means for vaporizing the oil, a partial combustion chamber for the vapor, an extinguishing chamber in communication with said partial combustion chamber, final combustion means in communication with said extinguishing chamber, and a separate oil supply pipe for said final combustion means, a portion of said pipe being in heating relation to said partial combustion chamber.

13. The combination comprising a partially consuming burner open at its opposite ends and having a nozzle disposed adjacent one of said ends, an oil supply pipe leading to said nozzle, a portion of said pipe being disposed adjacent the other open end of said burner, a pressure reservoir connected to said supply pipe, a valve regulating the flow of oil through said pipe, a final burner in operative relation to said partially consuming burner, and a second oil supply pipe leading to said final burner, a portion of said second oil supply pipe being disposed adjacent said other end of said partially consuming burner.

14. A portable oil burning apparatus comprising a base carrying liquid fuel force feeding means, vaporizing means, a vapor burner, an extinguishing chamber in line with said vaporizing means and adjacent the burner whereby to form a permanent combustible gas from said vaporized fuel, a gas passage leading from said extinguishing chamber, and a final burner connected to said gas passage.

15. A portable oil burning apparatus comprising a base carrying liquid fuel force feeding means, vaporizing means, a vapor burner, an extinguishing chamber in line with said vaporizing means and adjacent the burner whereby to form a permanent combustible gas from said vaporized fuel, a gas passage leading from said extinguishing chamber and containing said vaporizing means, and a final burner connected to said gas passage beyond said vaporizing means.

In testimony whereof I affix my signature, in presence of two witnesses.
